EDOUARD SEIGNOL, OF PARIS, FRANCE

CARBURETOR

Application filed June 25, 1927, Serial No. 201,382, and in France June 26, 1926.

The present invention relates to improvements in self feeding carburetors for internal combustion engines. The object of these improvements is to provide a carburetor for feeding an engine, especially a motor car, a motor boat or aeroplane engine, from a fuel tank located at a relatively great horizontal distance from the engine and at a substantially lower level. Another object of the invention is to dispense in such carburetors with the ordinary fuel exhauster or the like and with the constant level devices ordinarily used. A further object of the invention is to improve the efficiency and the working of the engine when slow running or at normal speed especially when the throttle valve being nearly fully or fully open the engine is submitted to variations in speed according to the load. A still further object of the invention is to provide for the engine a large torque at slow speed and, as a consequence, to dispense with a frequent use of the change speed gear on a motor car even when the engine is a small one comparatively to the weight of the car. Again a still further object of the invention is to ensure an economy in fuel consumption and a correct carburation for all speeds of the engine.

The invention is illustrated by way of example in the accompanying drawings.

In these drawings:

Fig. 1 shows a diagrammatic side elevation at small scale, of a chassis provided with a carburetor according to the present invention.

Fig. 2 shows a longitudinal section, at an enlarged scale, of the carburetor properly so called.

Fig. 2^a is a continuation of the right hand end of Fig. 2, showing the trap in the main fuel tank.

Fig. 3 shows a fragmentary cross section through A—A of Fig. 2.

Fig. 4 shows a longitudinal section through B—B of Fig. 2.

Fig. 5 shows an elevation on a still larger scale of a construction detail.

Fig. 6 shows a fragmentary cross section through C—C of Fig. 2.

Fig. 7 shows a fragmentary longitudinal

section, of a modification of the main mixing chamber shown in Fig. 2.

As shown in Figs. 1 to 6 the carburetor comprises two parts *a* and *b* connected together by a piping *c*. The part *a* is what may be called a primary carbureting device and produces a very rich carbureted mixture by mixing with air a great proportion of liquid fuel contained in a lower tank 1. The part *b* is what may be called a secondary carbureting device and admixes with the very rich carbureted mixture made by *a* the correct amount of air for feeding the engine 2 at any speed. The device *a* is located close to and above the fuel tank 1 at the rear of the chassis and at a relatively low level. The part *b* is located close to the motor and above the level of the fuel in tank 1.

The primary carbureting device *a* comprises a Venturi tube 3 with a convergent part 4 and a divergent part 5. The restricted portion 6 of this venturi communicates through a conditit 7—8 with a chamber 9 to which leads a pipe 10 secured, similarly to the venturi 3, in a plug 11 affixed on the fuel tank 1. The lower end of the tube 10 is located slightly above the bottom of the tank 1. A pipe 12 connects the divergent part of the venturi 3 to the secondary carbureting device *b*.

This device *b* comprises an inlet pipe 13 leading from a venturi 14 with a convergent part 15 and divergent part 16. In the inlet pipe is positioned the usual throttle valve 17 for regulating the flow of carbureted mixture to the engine. In the venturi 14 a little downstream from the throat 18 opens the pipe 12. Upstream to the venturi 14 is the air inlet 19. The opening of this inlet is controlled by a rotative throttle valve 20 mounted on trunnions 21—22 turning in a casing 23. It will be noted that this valve is pneumatically balanced against movement in response to differences in air pressure on opposite sides thereof, or variations in flow of air therethrough. The valve 20 is provided with two openings 24—25 and two solid parts 24^a—25^a. The opening 25 is capable of registering progressively with the air inlet 19 when the valve 20 turns in the direction of the arrow F, opening progressively this air in-

let until it is wide open, the openings 24—25 being as large as the air inlet 19.

On the trunnion 22 of the valve 20 is secured an arm 26 which is connected by links 27 to the rod 28 of a piston 29 movable in a cylinder 30. This cylinder communicates through the conduit 31 with the interior of the carbureting device B at a point between the valves 17 and 20 and preferably between the throttle 17 and the throat 18 and still more preferably at a point 32 in the divergent part 16 of the venturi 14. A spring 33 surrounding the trunnion 22 and fixed at one end to the casing 23 and at the other end to the arm 26 tends to force the piston 29 to the lower end of the cylinder 30 and consequently the valve 20 to close the air inlet 19, the solid part 25 coming to register with said air inlet.

When the throttle valve 17 is closed as shown in Fig. 2 no depression exists in the venturi 14 and no suction is exerted on the opening of the tube 32 in said venturi; no vacuum is transmitted to the cylinder 30 and the spring 33 closes the air inlet valve 20.

When for normal running the throttle has been opened the engine sets up a depression in the inlet pipe 13 and venturi 14 up to the air throttle 20. This suction acts through the tube 12 on the venturi 3. Air is sucked in said venturi and, as it passes through the throat 6 it sucks up liquid fuel through conduits 7 and 8, chamber 9 and tube 10 from the tank 1 making a very rich carbureted mixture which is conveyed through tube 12 to the venturi 14. The same suction acts also through the conduit 31 on the inside of the cylinder 30 then on the piston 29, which compresses the spring 33 and opens the air throttle 20.

When at normal speed the engine comes under such a load that it is forced to diminish speed although the throttle 17 is maintained open, the depression in the inlet 13 and venturi 14 is reduced; the carburetion is then influenced simultaneously in the device a and in the device b and is not, for the moment, kept at its best mixture. The variation of suction however comes into action to regulate air admission and the depression being less than when the engine was revolving at full speed, the spring 33 will force the piston 29 down to a certain extent and partially close the air throttle 20. The quantity of air admitted will consequently decrease and if the spring 33 is properly tensioned it will be possible to have the air decrease not only positively but also relatively to the amount of rich mixture produced by the device a and admitted in the device b.

The more the speed of the engine diminishes the less will be the depression in the venturi 14 and consequently the greater will be the extent to which the spring 33 will force the piston 29 downward and close the throttle 20. The regulation will consequently be continuous and by suitably determining the area

of the piston and the strength of the spring the best value for each speed of rotation of the engine for the admission of rich mixture and of air to the device b can be maintained. This regulating device not only maintains a correct regulation whatever may be the degree of opening of the throttle 17 but moreover it is particularly effective when the throttle 17 is fully open and the engine is under a variable load.

The carburetor as illustrated in Figs. 1 to 4 also comprises a slow running device which cooperates with the normal running device already described. This slow running device comprises a Venturi tube 34 having a convergent part 35, and a divergent part 36 and a throat 37 which communicates with a tube 38 leading close to the bottom of fuel tank 1. A pipe 39 connects the venturi 34 to a conduit 40 which opens in the inlet 13 downstream of the throttle valve 17. The cross section of said conduit is regulated by a needle valve 42 provided with longitudinal transverse passages 41 and 43 as shown. The passage 43 maintains a constantly open connection between the pipe 39 and the inlet 13 whilst the passage 41 provides for constant communication between atmospheric air and the said inlet.

The suction exerted by the engine is transmitted through the conduit 40 to the passages 41 and 43 and pipe 39 to venturi 34. Air is admitted in this venturi which sucks up liquid fuel from the tank 1, which fuel is admixed with the air entering the venturi and forms a very rich mixture which is conveyed to the inlet 13 through pipe 39.

There the rich mixture receives an addition of fresh air by the passage 41 in order to produce the slow running carbureted mixture.

When the engine is running slowly and not under load the throttle 17 is closed and it is fed only through pipe 39 by venturi 34. When running normally the throttle 17 is wide open and the engine is fed only through pipe 12 by venturi 3 as the passage 43 is a very small one. The depression is at that time very small in venturi 14 and the speed of air in venturi 34 is consequently too small to lift fuel from the tank 1. It may occur that for a certain position of the throttle 17 and for a certain speed of the engine the latter will be fed by both slow and normal running devices, the working effect of the throttle valve 20 acting on both said devices.

It should be stated that the valve 20 and its actuating device also serve to ensure a quick acceleration of the engine from slow to normal running when as aforesaid the conduit 31 is provided with a regulating needle valve 31^a. This valve 31^a acts to brake the movement of the piston 29 and thus to prevent the valve 20 from being opened too quickly when the throttle valve 17 is suddenly ac-

tuated for accelerating the engine to full speed. If the valve 20 be too quickly opened the suction would admit in the inlet a too large amount of air before the venturi 3 is again set in action and the column of air or carbureted mixture in tube 12 is set in motion. By braking the opening of the valve 20 when the throttle 17 is suddenly opened the suction transmitted to the venturi 14 first acts on the tube 12 and the venturi 3 and, at the same time, on the conduit 31 but as the vacuum acts slowly on the piston 29 the air valve 20 also opens slowly and air is admitted through 19 at the right time and in correct progressive proportions relatively to the rich mixture entering the venturi through 12.

The acceleration is also facilitated by the liquid fuel accumulated in the recess surrounding the throat of the venturi 3. When the sucking action of the venturi 3 ceases the fuel filling the chamber 9 partly flows in the recess above referred to and remains there. When the venturi 3 is again set in action it first sucks the fuel in the recess thus causing a slight excess of fuel to be added to the primary air enhancing the richness of the carbureted mixture which facilitates the acceleration.

To assure a better progressive working of the air inlet valve 20 the holes 25 can be V-shaped, saw-teeth or any other form which will ensure progressive opening or closing of the air passage during opening and closing movement of the air inlet valve.

In the modification shown in Fig. 7 the piston 29 instead of being actuated on one side by suction and on the other by a spring, is on the upper side actuated by depression in the downstream of the throttle 17 through the conduit 31 and on the other by depression created at the opening of a conduit 31^b in the throat 18 of the venturi. It is thus actuated by differential suction. When the throttle 17 is closed and the carburetor works by means of its slow speed device (similar to that of the carburetor of Fig. 2 but not shown) opening at 40 in the inlet 13, the suction in the downstream of 17 draws the piston 29 upwards then closing the air throttle 20 (illustrated as a butterfly valve) as shown in the figure, which allows even then a slow admission of air. When the throttle 17 is open the depression at 31^b being greater than that at 31 draws the piston down and opens the throttle 20. The throttle 17 being nearly or fully open, if the engine attempts to vary in speed, the depression in the carburetor changes, the difference between the depressions at 31 and 31^b will vary similarly and the piston will be displaced by the new difference until the piston having operated the air inlet apparatus the suction in the carburetor regains its normal value thus reestablishing the equilibrium of the air regulating system.

In Figs. 2 and 6 is illustrated a device for obtaining a greater regularity in the production of the very rich carbureted mixture by means of the device *a*. The fuel tank is closed and air tight and a tube 44 is provided which leads from the bottom of the tank and opens in the atmosphere. A passage 45 connects the upper part of the tank 1 to the throat 37 of venturi 34. For any speed of the engine a depression is created in the tank by the engine through the conduit 40, the tube 39, the venturi 34 and the passage 45, air being sucked up by venturi 34 through passage 45. Owing to this suction the liquid fuel is depressed by the atmospheric pressure in tube 44 and air passes through the lower end of said tube. By these means the effective weight of the liquid fuel as regards the venturis 3 and 34 is always the same whatever may be the level of the fuel in the tank 1 and the venturis work exactly under the same conditions as if the level of the fuel in the tank was constant.

In order to prevent entrance of air into the tank and at the same time prevent any excess of pressure in the tank by heat or other reasons which could cause the fuel to be expelled through the tube 44, the tank is provided with a check valve 46 having a seat 47.

The present invention can be considered as a modification or improvement of that described in my U. S. application Serial No. 90,958 of February 26, 1926 in that in the present invention the suction on the piston regulating the auxiliary valve is not produced by the depression on the downstream side of the throttle, but in the upstream side, with a spring or similar element tending to close the valve opposed to the suction in order to open the air inlet shutter other than by the effect of the current of air entering the carburetor under direct influence of the engine suction. From this it results that the regulation which before was relatively rapid and only applied during the period of passing from slow to normal running, is now produced at all times.

The invention can moreover for the same reasons be considered as an improvement of the carburetor described in my U. S. A. application Serial No. 91,586 of March 1, 1926.

It is seen that a carburetor constructed according to the present invention produces great flexibility of control of the engine, allowing it to descend to an extremely low speed of rotation with a high degree of torque. This is due to the fact that the regulation of air supply in the carburetor (primary and secondary carburetor) is such as to prevent the carbureted mixture from becoming too poor as regards fuel when at slow speed the throttle valve is widely opened. Thus the engine cannot choke owing to much air entering the carburetor.

What is claimed is:

1. In a self-feeding carburetor the combination of an internal combustion engine in-

take, a main liquid fuel tank located at a lower level than the said intake, a primary venturi positioned above the level of the fuel in the main tank and close to said tank, a conduit connecting the throat of the venturi directly to a point slightly above the bottom of the tank, a secondary venturi in the intake, a throttle valve downstream the secondary venturi regulating the flow of carbureted mixture to the engine, a piping connecting the primary venturi to a point slightly downstream of the throat of the secondary venturi therein, a pneumatically balanced air throttle valve regulating the flow of air in the secondary venturi and influencing the flow of air in the primary venturi, a piston movable in a cylinder, a cylinder exhaust conduit connecting one face of the said piston with a point located between the two throttle valves, a spring tending to close the air regulating throttle valve and a connection between the said piston and the said air regulating throttle valve, the movements of the piston under the influence of the depression above referred to and of the said spring causing the air regulating throttle valve to be moved towards its closure position when the depression diminishes and vice versa and means for regulating the section of the said cylinder exhaust conduit.

2. In a self-feeding carburetor the combination of an internal combustion engine intake, a main liquid fuel tank located at a lower level than the said intake, a primary venturi positioned above the level of the fuel in the main tank and close to said tank, a conduit connecting the throat of the venturi to a point slightly above the bottom of the tank, a secondary venturi in the intake, a throttle valve downstream, the said secondary venturi regulating the flow of carbureted mixture to the engine, a piping connecting the primary venturi to a point within the secondary venturi slightly downstream the throat of the secondary venturi, an air throttle valve regulating the flow of air in the secondary venturi and influencing the flow of air in the primary venturi, a second primary venturi located as the first primary one and connected to the bottom of the tank, a second piping connecting the said second primary venturi to the intake of the engine at a point positioned downstream of the regulating throttle valve therein, means for admixing air to the carbureted mixture delivered by the second primary venturi, a piston movable in a cylinder, a conduit connecting one face of the said piston with a point located between the two throttle valves, a spring tending to close the air regulating throttle valve and a connection between the said piston and the said air regulating throttle valve the movements of the piston under the influence of the depression between the two throttle valves and of the said spring,

causing the air regulating throttle valve to be moved toward its closure position when the depression diminishes and vice versa.

3. In a self-feeding carburetor for internal combustion engines, the combination of an air tight main liquid fuel tank located at a lower level than the engine intake, a primary venturi positioned above the level of the fuel in the main tank and close to said tank, a conduit connecting the throat of the venturi to a point slightly above the bottom of the tank, a secondary venturi in the intake, a throttle valve downstream the said secondary venturi regulating the flow of carbureted mixture to the engine, a piping connecting the primary venturi to a point slightly downstream the throat of the secondary venturi therein, an air throttle valve regulating the flow of air in the secondary venturi and influencing the flow of air in the primary venturi, a second primary venturi located as the first primary one and connected to the bottom of the tank, a piping connecting the said second primary venturi to the intake of the engine at a point positioned downstream of the regulating throttle valve therein, means for admixing air to the carbureted mixture delivered by the second primary venturi, a passage connecting the throat of the said second primary venturi to the inside of the said fuel tank above the level of the fuel therein, and a tube opening at one end to the atmosphere and at the other end close to the bottom of the tank.

4. In a self-feeding carburetor the combination of an internal combustion engine intake, an air tight liquid fuel tank located at a lower level than the said intake, a primary venturi positioned above the level of the fuel in the tank and close to said tank, a conduit connecting the throat of the venturi to a point slightly above the bottom of the tank, a secondary venturi in the intake, a throttle valve downstream of the said secondary venturi regulating the flow of carbureted mixture to the engine, a piping connecting the primary venturi to a point slightly downstream of the throat of the secondary venturi, an air throttle valve regulating the flow of air in the secondary venturi and influencing the flow of air in the primary venturi, a second primary venturi located as the first primary one and connected to the bottom of the tank, a second piping connecting the said second primary venturi to the intake of the engine at a point positioned downstream of the regulating throttle valve therein, means for admixing air to the carbureted mixture delivered by the second primary venturi, a passage connecting the throat of the said second primary venturi to the inside of the said fuel tank above the level of the fuel therein, a tube opening at one end to the atmosphere and at the other end close to the bottom of the tank.

end close to the bottom of the tank, a piston
movable in a cylinder, a conduit connecting
one face of the said piston with a point lo-
cated between the two throttle valves, a
5 spring tending to close the air regulating
throttle valve, and a connection between the
said piston and the said air regulating
throttle valve, the movements of the piston
under the influence of the depression above
10 referred to and of the said spring causing
the air regulating throttle valve to be moved
towards its closure position when the de-
pression diminishes and vice versa.

15 In testimony whereof I have affixed my
signature.

EDOUARD SEIGNOL.
